HAND LAMP

Walter R. Kopp, New Haven, Conn., assignor to
 Western Cartridge Company, New Haven,
 Conn., a corporation of Delaware

Application March 20, 1941, Serial No. 384,281

4 Claims. (Cl. 240—10.66)

This invention relates to hand lamps and more particularly to a supporting device for a hand lamp bulb.

In the older construction of hand lamps the lamp bulb is provided with a threaded stem and the casing is provided with a threaded socket to receive the stem of the bulb. The newer hand lamp bulb of the prefocused type is provided with a lateral flange surrounding the stem and this flange engages a seat on the reflector to hold the bulb in position. Suitable means are provided for maintaining the flange of the bulb against the seat of the reflector. The seat must be accurately positioned to dispose the lamp portion of the bulb in the proper place within the reflector for focusing.

The present invention comprises an adapter to permit the use of bulbs having threaded stems with hand lamps built to receive bulbs of the prefocused type. In carrying out the invention I provide an internally threaded sleeve which is adapted to receive the threaded stem of the lamp bulb and which is provided with a flange adapted to engage the seat formed on the reflector. Because of the threaded connection between the adapter and the lamp bulb the lamp bulb may be properly adjusted for focusing. The lamp bulb is retained in position by means of a cup-shaped member which is threaded to the reflector, the base of which bears against the base of the lamp bulb to hold it in position. The base of the cup-shaped member is in turn provided with an opening through which the base terminal of the bulb projects to engage the central electrode of the upper cell of the battery.

In the accompanying drawing I have shown one embodiment of the invention. In this showing:

Fig. 1 is a longitudinal, sectional view of the end of a hand lamp casing showing the invention applied;

Fig. 2 is a similar view of a portion of the reflector;

Fig. 3 is a detailed view of the lamp bulb and adapter; and

Fig. 4 is a sectional view of the cup-shaped member.

Referring to Fig. 1 of the drawing the reference numeral 1 designates generally a portion of a hand lamp casing having a flared upper end 2 and having a battery therein consisting of one or more cells, the end of the upper cell being shown at 3. The cell is provided with a central electrode 4 which is adapted to be engaged by the base terminal of a lamp bulb in the usual man-

ner. The enlarged head of the casing is threaded as at 6 and is provided with a flange 7. A reflector 8 is provided with a peripheral flange 9 which is adapted to be supported by the flange 7. A ring 10 of insulating material may be arranged around the flange of the reflector. A lens 11 is arranged on the flange of the reflector. The reflector and lens are retained in position by an end cap 12 which is internally threaded to engage the threads 6 on the end of the casing.

The reflector is constructed to receive a bulb of the prefocused type. As shown it is provided with a central opening 13. An externally threaded member 14 is secured to the reflector around this opening. As shown the member 14 is provided with a portion 15 of reduced diameter and the portion 15 has an inwardly extending flange 16 on its end. The material of the reflector around the opening 13 is spun over this flange as indicated at 17. Between the threaded portion 14 and the portion 15 of reduced diameter the shoulder 14' forms a seat for the reception of the flange arranged on the stem of a bulb of the prefocused type.

The adapter shown in detail in Fig. 3 of the drawing consists of an internally threaded sleeve 18 having a flange 19 on one end. This adapter receives a bulb 20 having a threaded stem 21. The bulb is provided with a central terminal 22 connected to one end of the filament by a suitable lead wire (not shown) and the other terminal is connected to the threaded shell 21 by suitable lead wire as is usual in the construction of bulbs of this type. The lead wires are embedded in insulating material within the shell and this insulating material is exposed at the bottom of the stem around the central terminal as indicated at 23.

When the bulb and adapter are in position in the lamp as shown in Fig. 1, the flange 19 of the adapter engaging the seat 14' limits the forward movement of the bulb into the reflector. The cup-shaped member shown in Fig. 4 of the drawing engages the base of the bulb to retain it in position and retain the flange 19 against the seat 14'. As shown the cup-shaped member comprises an internally threaded sleeve 24 which engages the threads 14. The bottom of the cup-shaped member is provided with an inclined portion 25 and a substantially horizontal portion 26. This horizontal portion 26 is provided with a central opening 27. The base terminal of the bulb projects through the opening 27 to engage the central terminal 4 of the battery. The other terminal of the battery is connected to the outer

terminal of the lamp bulb by a movable switch member 28 which is adapted to be moved in and out of contact with the reflector by any suitable switch means (not shown) mounted on the casing. To prevent short circuiting of the lamp it is thus necessary to insulate the cup-shaped member 24 from the central terminal. The indented portion in the bottom of the cup-shaped member formed by the inclined wall 25 is provided for this purpose and the horizontal portion 26 of the cup-shaped member surrounding the opening engages the insulation 23 and is thus insulated from the central terminal 22 of the lamp bulb.

It will be apparent that the construction described thus provides a very simple means for mounting a lamp bulb having a threaded stem in a hand lamp reflector built for the reception of a bulb of the prefocused type. In employing prefocused bulbs it is necessary that the seat 14 be very accurately positioned to arrange the lamp portion of the bulb in focus when it is mounted in the reflector. In employing the present construction with the type of bulb disclosed, this is not necessary because the bulb may be adjusted in the adapter, due to the threaded engagement to bring it into focus when it is arranged in the reflector.

I claim:

1. A hand lamp comprising a reflector having a central opening and having a seat formed adjacent the opening, a threaded sleeve having a flange engaging the seat, a lamp bulb having a threaded stem received in the sleeve, the bulb having a terminal on the end of the stem, and a cup-shaped member connected to the reflector and engaging a portion of the base of the lamp bulb to exert an axial pressure on it and retain it in position, the cup-shaped member having a central opening through which the base terminal of the lamp projects.

2. A hand lamp comprising a reflector having a central opening and having a seat formed ad-

jacent the opening, a threaded sleeve having a flange engaging the seat, a lamp bulb having a threaded stem received in the sleeve, the bulb having a terminal on the end of the stem, and a cup-shaped member connected to the reflector and engaging the base of the lamp bulb stem to retain the lamp bulb in position, the bottom of the cup-shaped member being inclined inwardly adjacent its periphery and being provided with a central opening through which the base terminal of the lamp bulb projects.

3. A hand lamp comprising a reflector having a central opening, an externally threaded cylindrical member secured to the reflector adjacent the opening, said member being provided with a seat, a threaded sleeve having a flange engaging the seat, a lamp bulb having a threaded stem received in the sleeve, the lamp bulb having a terminal on the base of the stem, and a cup-shaped member connected to the cylindrical member and engaging a portion of the base of the lamp bulb to exert an axial pressure on it and retain the lamp bulb in position, the cup-shaped member being provided with a central opening through which the base terminal of the lamp bulb projects.

4. A hand lamp comprising a reflector having a central opening, an externally threaded cylindrical member secured to the reflector adjacent the opening, said member being provided with a seat, a threaded sleeve having a flange engaging the seat, a lamp bulb having a threaded stem received in the sleeve, the lamp bulb having a terminal on the base of the stem, and a cup-shaped member connected to the cylindrical member and engaging a portion of the base of the lamp bulb to retain the lamp bulb in position, the bottom of cup-shaped member being inclined inwardly adjacent its periphery and being provided with a central opening through which the base terminal of the lamp bulb projects.
